LIFTING TOOL FOR BUILDING BLOCKS

Clayton J. Ellis, 1 Green Mountain Place, Middlebury, Vt., and Frederick C. McLaughlin, Poultney, Vt.

Filed Dec. 31, 1957, Ser. No. 706,392

2 Claims. (Cl. 294—62)

The present invention relates to an improved hand tool or implement through the medium of which a user thereof may readily catch hold of a concrete or similar building block, lift it, carry it, and otherwise handle it as is done with the aid of similarly constructed tools commonly referred to in the art as lifting and carrying tongs.

As the preceding statement of the invention reveals, many and varied styles and forms of block lifting and handling tools have been devised by others. The present invention relates, obviously, to a structurally different tool which, it is believed, is not only simpler in construction but is easier to use, is highly efficient in accomplishing the ends desired, and is otherwise aptly suited to comply with manufacturing requirements and the need for a tool which may be not only quickly engaged with the block but just as easily released from the block.

Some users of tools in this category of invention employ a single hand for lifting and carrying requirements. Others find it necessary to employ both hands. It is an object of the present invention to provide a tool which is characterized by a handle having a central hand-grip for single handed use and optional hand-grips at the left and right end portions which may be used when both hands are needed.

More specifically, novelty is predicated on a handle having a centrally mounted hand-grip for single-handed use and optional hand-grips at its respective end portions for use when both hands are needed, a first leg rigidly attached to and depending from one end portion of the handle, said leg being provided at its lower end portion with at least one block engaging and gripping member, and a second leg supplemental to said first leg and depending from said handle, fixed thereon and spaced from the other end portion of the first leg and provided at its lower end with a spring biased pivotally mounted block engaging and gripping member.

Further novelty is directed to a construction wherein each leg is provided adjacent the upper end with a cross-head which is shaped to guidingly pilot the leg into the intended operating position and is also shouldered to limit the degree of insertion of the leg into the opening in the block.

Other objects, features and advantages will become more readily apparent from the following description and the accompanying drawings.

In the drawings, wherein like numerals are employed to designate like parts throughout the views:

Fig. 1 is a view of a concrete block in section and showing the improved lifting and handling tool with parts in section and elevation and with the gripping pins engaged.

Figs. 2, 3 and 4 are sections on the lines 2—2, 3—3 and 4—4, respectively, of Fig. 1.

Referring now to Fig. 1 the building block (cement or an equivalent material) is denoted by the numeral 6 and the usual cored openings in the block are denoted at 8.

2

The handle as an entity is denoted by the numeral 10 and it comprises a linearly straight rod member of requisite length denoted at 12, provided at the center with one hand grip 14 and at the respective left and right ends 5 with additional hand-grips 16 and 18. As explained the center grip 14 is for single-handed use and the end grips 16 and 18 are used with both hands when needed.

The first depending leg is denoted at 20 and has a straight lower end portion 22 which parallels the wall of 10 the opening 8 and is provided with upper and lower pointed gripping pins 24 and 26. The upper end portion is formed into a split-collar 28 the portions of which 15 embrace the part 30 of the hand-grip and are fastened thereto by clamping bolt 32. The handle has a keyway 34 into which a key 36 carried by the collar is fastened. The upper portion of the leg, denoted at 38, depends at right angles from the axis of the handle and the intermediate portion 40 is disposed at an oblique angle and has a cross-head 42 which as shown in Fig. 2 has stop 20 shoulders 44 and converging edge portions 46 defining a pilot to assist in feeding the leg into the opening 8 positioning it and regulating it when the stops 44 come into the position shown.

The second companion leg is denoted by the numeral 48 and inasmuch as it is structurally the same insofar as the principal components are concerned, the same reference numerals are used to designate like parts. There is a difference however in the lower end construction which, as shown in Fig. 4, is bifurcated to provide a pair 30 of spaced furcations. These furcations straddle a block-like member 50 which is fitted between the furcations 52 and is removably pivoted in place at 54. The block-like member carries a pointed pin or prong 56 which, like the pins 24 and 26, is adapted to be embedded in the surface 35 of the block to obtain the desired grip. There is a coil spring 58 provided and this spring is parallel to the leg 48 and is anchored at the upper end at 60 and has its lower end 62 connected to the pivoted block 50 to exert a pull in a direction to keep the pin 56 engaged with the 40 wall surface.

It will be evident that in use the legs are inserted into the respective cored holes 8 in the block 6, said legs being, by reason of their particular construction, self-centering. The block can then be lifted with one hand using the 45 center hand-grip 14 or with both hands using the outer grips 16 and 18. To release all that is necessary is to exert a slight upward pull on the grip 16 above the leg 20. As is evident, the coil spring 58 keeps the pivoted block 50 under tension to maintain the pointed pin 56 in its desired gripping position.

The foregoing is considered as illustrative only of the principles of the invention. Further, since numerous modifications and changes will readily occur to those skilled in the art, it is not desired to limit the invention to the exact construction and operation shown and described, and accordingly all suitable modifications and equivalents may be resorted to, falling within the scope 55 of the invention as claimed.

What is claimed as new is as follows:

1. For use in handling and carrying a concrete building block, a manually usable lifting tool comprising a rigid elongated handle straight from end to end, a primary hand-grip for balanced single-handed use mounted on said handle midway between the respective ends of the handle, auxiliary hand-grips mounted on the respective 60 end portions of said handle and adapted to be simultaneously gripped when both hands of the user are needed in satisfactorily catching hold of and using the handle, a first leg having a lower end portion disposed at right angles and transversely to the axis of said handle, pointed 65 block engaging and lifting members fixed to and projecting outwardly from said lower end portion of the first leg,

a median portion of said leg slanting upwardly and inwardly from the lower end portion of the first leg, the upper end portion of said first leg being disposed at an approximate right angle to the axis of the handle and being provided with a collar embracing and removably clamped on a portion of said handle at the inner end of an adjacent auxiliary hand-grip and an adjacent end portion of said primary hand-grip, a second leg of a length corresponding to the length of said first leg and disposed transversely of the axis of said handle in spaced relation from the first leg, the upper end portion of said second leg being secured to the handle between the inner end of the other auxiliary hand-grip and the adjacent end of the primary hand-grip, the major portion of said second leg extending downwardly and outwardly from said handle, a spring-biased member pivotally mounted on the lower end of said second leg, and an outwardly projecting pointed gripping pin provided on said spring-biased member and adapted to engage a cooperating surface of the block to be lifted, portions of said first and second legs below said handle being provided with correspondingly constructed cross heads the portions of which are at right angles to the lengthwise axes of said legs, said cross heads having outstanding portions constituting stops adapted to

20

rest atop the block and to limit the descent of the lower end portions of the legs into the openings provided thereor in said block.

2. The devices as defined in claim 1 wherein the lower end of said second leg is bifurcated, said spring-biased member being pivotally mounted between the furcations of said bifurcated leg end, the spring-biasing means of said member comprising a tension spring disposed inwardly of the second leg and anchored at one end thereof to an upper end portion of the latter, the other end of said spring being anchored to said member whereby to pivotally urge the same to a position wherein said pin is in gripping engagement with said cooperating surface of the block to be lifted.
